SKATE

William H. Decker, Shawnee, Okla.

Application July 26, 1938, Serial No. 221,281

5 Claims. (Cl. 280—11.25)

This invention relates to skates and more particularly to two-wheeled skates, the two wheels of which are not in longitudinal alignment.

The principal objects of the invention are to provide a novelty skate which requires more than ordinary skill for its operation and yet which has advantages over ordinary skates after sufficient skill has been acquired to use it properly; to provide a skate with sufficiently large wheels that the balance of the user is not noticeably effected when the wheels pass over small obstacles or irregularities in the surface over which the skate is travelling, and yet which elevates the user only very slightly more than do conventional skates; to provide a skate the wheels of which may be fitted with either solid or pneumatic rubber tires without the difficulty in changing, repairing or replacing the tires which would be present if conventional skates were so equipped; to provide a two-wheeled skate, the foot supporting frame of which is so balanced between the forward and the rear wheel that it is much easier to change the direction of travel of the skate than to do so with conventional two-wheeled skates.

A further object of my invention is to provide a skate which not only has these special attributes, but which is also possessed of the usual attributes of simplicity, cheapness of manufacture, and reliability.

The details in the construction of a preferred form of my invention, together with other objects attending its production, will be better understood from the following description when read in connection with the accompanying drawing, which is chosen for illustrative purposes only, and in which,

Figure 1 is a perspective view of a preferred embodiment of my invention with certain parts shown only fragmentarily.

Figure 2 is a transverse sectional view taken through the front wheel assembly;

Figure 3 is a diagrammatic view taken from the rear of the skate showing particularly the angle at which the wheels are mounted; and

Figure 4 is a diagrammatic plan view of the invention.

The invention includes a transverse foot plate which is designated as a whole in the drawing by the numeral 5, and which is composed of a sole plate 6 and a heel plate 7. These two are connected together in alignment for lengthwise adjustment by means of a bolt and nut 8 passing through aligned slots in the respective plates.

The nether surface of each plate is provided with

braces or bracing ribs 9 and 10. The sole plate is also provided with an upwardly extending shoe guard 11 and an adjustable strap 12 for firmly securing the shoe of a wearer to that plate.

Similarly, the heel plate is provided with a heel guard 13 and an adjustable ankle strap 14 for firmly positioning the rear portion of the shoe on that plate. This heel plate is also provided with an upright leg brace 15 which includes a longitudinally extending strengthening rib 16, a flared arcuate upper end 17, and a leg strap 18.

The front and rear wheel assemblies are identical in construction so that it will be necessary only to describe one wheel assembly. One complete assembly includes a bearing block 19 which is transversely bored to receive any suitable type bearings and bearing races 20 and 21 and bearing cones 22 and 23, which journal an axle 24. One end of the axle carries a wheel 25 which is preferably fitted with a tire 26. The tire, of course, may be either of the solid rubber type or of the pneumatic type. Preferably conical roller bearings and cones are used as shown, although ball bearings may be used without departing from the spirit of the invention. With this conical bearing mounting, the wheel hub 27 is of such diameter as to contact the outer end of the cone 23 without contacting any portion of the bearing or bearing race 21 and without contacting any portion of the bearing block 19. The other end of the axle is fitted with a washer 28 of a diameter identical to that of the wheel hub 27, which washer is held snugly against the cone 22 by a lock nut 29 and cotter pin 30. As previously stated, a different type bearing may be used and a different wheel mounting may be used. The rotation of the wheel 25 on the axle 24 rather than the rotation of the two together would not affect the inventive principle.

As shown, the bore in the bearing block 19 is not parallel to the plate on which the block is mounted but extends at an angle thereto.

Both the front and rear wheel assembly bearing blocks are preferably rigidly secured to their respective plates, but I wish to point out that an adjustable or pivotal mounting of either the front or rear wheel bearing blocks would not amount to invention over the preferred embodiment as shown.

The front and rear wheel assemblies are mounted on the transverse foot plate 5 in the manner shown in Figures 1, 3 and 4 so that the front wheel is on the outside of the skate and the rear wheel is on the inside of the skate. This

makes the axis of balance of the skate lie at an angle to the direction of travel. In Figure 4 the line $x-x$ represents the direction of travel of the skate while the line $y-y$ represents the axis of balance. With the wheels mounted as shown they rotate respectively in planes which meet each other at an acute angle along a line directly beneath and parallel to the longitudinal axis of the plate, which longitudinal axis also coincides with the normal direction of travel of the skate. In order to differentiate between the front and rear wheels in the various views I have numbered the front wheel 31 and the rear wheel 26 although the two wheels are identical in size and shape.

While I have described and illustrated a specific embodiment of my invention, I am aware that numerous alterations and changes may be made therein and I do not wish to be limited except by the prior art and by the scope of the appended claims.

I claim:

1. A two-wheeled roller skate comprising: a lengthwise adjustable transverse foot plate; a front wheel mounted along the outside edge of said plate; and a rear wheel mounted along the inside edge of said plate, said wheels respectively adapted to rotate in planes which meet each other at an acute angle along a line directly beneath and parallel to the longitudinal axis of said plate.
2. A two-wheeled roller skate comprising a sole plate and a heel plate connected in alignment; a front wheel mounted along the outside edge of said sole plate; and a rear wheel mounted along the inside edge of said heel plate, said wheels respectively adapted to rotate in planes which meet at an acute angle along a line directly

beneath and parallel to the common longitudinal axes of said sole and heel plates.

3. A two-wheeled roller skate comprising a sole plate and a heel plate connected in alignment; a front wheel mounted along the outside edge of said sole plate; and a rear wheel mounted along the inside edge of said heel plate, said wheels respectively adapted to rotate in planes which meet at an acute angle along a line directly beneath and parallel to the common longitudinal axes of said sole and heel plates; and means for securing said plates to the foot of a wearer.

4. A two-wheeled skate comprising: a sole plate; a heel plate connected thereto for lengthwise adjustment; a wheel mounted adjacent the outside edge of said sole plate; another wheel mounted adjacent the inside edge of said heel plate, the axes of the two said wheels sloping downward and outward in opposite directions from the common longitudinal axis of the two said plates; and means carried by each of said plates for securing the skate to the foot of a wearer.

5. In a roller skate the combination of: a lengthwise adjustable transverse foot plate; a pair of roller bearing blocks rigidly mounted on the nether surface of said foot plate, one near the forward end and one near the rear end; a pair of axles each having one end rigidly connected to a wheel, said axles respectively being mounted in said roller bearing blocks in such a manner that they slope downwardly and outwardly in opposite directions from the longitudinal axis of said foot plate, said wheels being positioned on opposite sides of said longitudinal axis; and means for securing the skate to the foot of a wearer.

WILLIAM H. DECKER.
